FIG. 2.

Benjamin Green

UNITED STATES PATENT OFFICE

108,729

DESIGN FOR A GIRDLE OR SIMILAR ARTICLE

Benjamin Green, New York, N. Y.

Application December 17, 1937, Serial No. 73,665

Term of patent 3½ years

To all whom it may concern:

Be it known that I, Benjamin Green, a citizen of the United States of America, residing in New York city, in the Borough of Manhattan, county and State of New York, have invented a new, original, and ornamental Design for a Girdle or Similar Article, of which the following is a specification, reference being had to the accompanying drawing, forming part thereof, wherein,

The rear portion of the girdle, or similar article is substantially the same as the front.

The characteristic feature of my design resides in the combination on the girdle disclosed of the arrangement of the three specific weaves, as shown.

I claim:

The ornamental design for a girdle or similar article, substantially as shown, and described.
